(57) **CLAIM**

The ornamental design for a table base, as shown and described.

DESCRIPTION

FIG. 1 is a perspective view of a table base in accordance with the new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top view thereof;

FIG. 7 is a perspective view of an alternative embodiment of the table base; and

FIG. 8 is a front elevational view thereof;

FIG. 9 is a right side elevational view thereof;

FIG. 10 is a left side elevational view thereof;

FIG. 11 is a rear elevational view thereof; and,

FIG. 12 is a top view thereof.

The table base is shown broken away along its width and height in FIGS. 7-11. The appearance of any portion of the table base in-between the breaks forms no part of the claimed design.

The broken lines in the figures illustrate environment and form no part of the claimed design.

1 Claim, 8 Drawing Sheets
